The ornamental design for a portable rebounding device, as shown and described.

DESCRIPTION

FIG. 1 is an isometric view of a first embodiment of a portable rebounding device showing our new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an isometric view of a second embodiment of a portable rebounding device showing our new design;

FIG. 9 is a front elevational view thereof;

FIG. 10 is a back elevational view thereof;

FIG. 11 is a left side elevational view thereof;

FIG. 12 is a right side elevational view thereof;

FIG. 13 is top plan view thereof; and,

FIG. 14 is a bottom plan view thereof.

Those portions of the figures that are presented in broken lines merely illustrate the environment of the design and are not part of the claimed design.
